United States Patent Office

Des. 182,109
Patented Feb. 18, 1958

182,109

STORAGE BATTERY CASE

Ronald M. Fiandt, Wauwatosa, and Roy E. Hennen, Milwaukee, Wis., assignors to Globe-Union Inc., Milwaukee, Wis., a corporation of Delaware

Application January 28, 1957, Serial No. 44,633

Term of patent 14 years

(Cl. D26—6)

Fig. 1

Fig. 2

Fig. 3

Fig. 4

Fig. 1 is a view in front side elevation of a storage battery case, showing our new design;

Fig. 2 is a view in right-end elevation;

Fig. 3 is a view in rear side elevation; and

Fig. 4 is a view in left-end elevation.

The dominant features of our design reside in those portions shown in full lines.

We claim:

The ornamental design for a storage battery case, as shown and described.
